UNITED STATES PATENT OFFICE

144,677

DESIGN FOR A COUCH OR THE LIKE

Philip Billet and Irving Levy, New York, N. Y.

Application July 16, 1945, Serial No. 120,726

Term of patent 14 years

(CL. D5—4)

To all whom it may concern:

Be it known that we, Philip Billet and Irving Levy, citizens of the United States, residing at New York, in the county of the Bronx and State of New York, have invented a new, original, and ornamental Design for a Couch or the like, of which the following is a specification, reference being made to the accompanying drawing, forming a part thereof.

Fig. 1 is a perspective view of a couch or the like embodying our new design;

Fig. 2 is a left-hand end view of Fig. 1.
The other side of the design is the same as that shown in the drawing.

We claim:
The ornamental design for a couch or the like, substantially as shown and described.

PHILIP BILLET.
IRVING LEVY.
